PYRAZOLE-1-CARBOXAMIDINES

Horace Fletcher III, Pottstown, and Harvey E. Alburn, West Chester, Pa., assignors to American Home Products Corporation, New York, N.Y., a corporation of Delaware

No Drawing. Filed Feb. 4, 1963, Ser. No. 256,115

3 Claims. (Cl. 260—310)

This invention relates to new carboxamidine compounds having valuable pharmacological properties. More particularly this invention relates to new substituted carboxamidines and to the methods by which such compounds are prepared.

The new compounds of the present invention may be represented by the Formula I

wherein R is a 5 to 6 membered nitrogen containing heterocycle and tetrahydroisoquinolino, R¹ is selected from the group consisting of hydrogen, and

wherein R² is an alkyl radical and A is selected from the group consisting of hydrogen,

in which R³ is an alkyl group having not more than 7 carbon atoms, and —S(O)₂R⁴ in which R⁴ is aryl or alkaryl; together with their acid salts. In the foregoing structure, the heterocyclic R group includes pyrrolidino, morpholino, pyrazolino, pyrazolo and piperidino, all of which may be substituted with lower alkyl, di-lower alkyl and tri-lower alkyl radicals.

A preferred group of compounds within the class represented by Formula I above constitutes those represented by the following structural Formula II:

wherein R represents a member of the group consisting of piperidino, morpholino, pyrrolidino and pyrazolo together with the lower alkyl and di-lower alkyl homologs of each of these and tetrahydroisoquinolino; R¹ represents

or hydrogen; A is selected from the group consisting of hydrogen,

in which R² is an alkyl radical having not more than 7 carbon atoms and

in which R³ is selected from the group consisting of aryl and alkaryl; together with their pharmacologically acceptable acid salts.

As has been suggested, the new compounds of the present invention possess valuable pharmacological properties. More specifically, the new compounds of the present invention are useful as hypoglycemic agents. When used for the foregoing purposes, the new compounds are administered in dosage amounts of from 10 to 100 m./kg. either orally or parenterally in liquid or solid dosage

2

forms. When used with such carriers, the compound will be present in the carrier in an amount of from 0.1 to about 25 percent by weight. Dosage forms include injectables, elixirs, capsules, lozenges and tablets together with appropriate liquid or solid vehicles, excipients or carriers according to conventional pharmaceutical practice.

According to one method of preparation, the new compounds of the present invention are prepared by reacting a carboxamidine salt such as for example 3,5-dimethyl-pyrazole-1-carboxamidine nitrate, with excess acetic anhydride and excess triethylamine or trimethylamine or an equivalent tertiary base having a higher ionization constant than that of the pyrazole base starting material, in an alcohol solution. The alcohol used is preferably a low molecular weight alcohol such as methanol, ethanol or the like. The reaction mixture is allowed to stand for a period of time such as from 30 minutes to 24 hours at room temperature or lower. Temperatures higher than room temperature are not preferred. The alcohol is then removed, as by distillation, and the oil product dissolved in water and extracted in low molecular weight, water immiscible, ether or ester solvent such as diethyl ether or ethyl acetate. The ethereal or ester solution is dried, filtered and evaporated. The residue containing the desired compound, can then be recrystallized from ether or if desired the salt can be prepared, such as for example the hydrochloride, by passing HCl through the ethereal solution of the product. The resulting crystalline hydrochloride is then recovered by filtration.

The monoacetyl compounds of the present invention, other than the pyrazole derivatives, may be prepared by first reacting a selected carboxamidine salt with one equivalent of an anhydrous alcohol solution of sodium. The sodium salt resulting is filtered off and the filtrate evaporated to dryness. The solid residue obtained is then suspended in excess ethyl acetate and refluxed with stirring for a period of from 10 to 30 hours. The reaction mixture is then filtered and the filtrate evaporated to dryness. The residue is washed, preferably with ether, and the ether insoluble portion dissolved in hot ethyl acetate from which the desired monacetyl derivative is obtained on cooling.

In the foregoing methods of preparation, the selected carboxamidine salt, such as for example the 3,5-dimethyl-pyrazole-1-carboxamidine nitrate referred to above, is prepared according to the method of Theile, Annalen der Chemie, 302, 275-311 (1898). In this method, 1 mole of aminoguanidine nitrate is added, over a period of 1½ hours to 1 mole of 2,4-pentanedione in ethanol. After refluxing for 2½ hours, the nitrate salt is obtained on cooling to 0° C. To prepare other suitable heterocyclic carboxamidines, the salt of 3,5-dimethylpyrazole carboxamidine is reacted with the free base, such as for example pyrrolidine, piperidine or the like, in a low molecular weight alcohol solution for a period of from 1 to 3 hours. Suitable alcohols for this purpose include methanol, ethanol and the like. An amidine shift occurs in which the pyrrolidine replaces the dimethyl pyrazole, yielding the desired pyrrolidine carboxamidine salt. This product, in the form of the nitrate salt, may then be converted to the sulfate form if desired by treating with sulfuric acid in ethanol. In a similar manner, the other starting compounds identified in the examples which follow are prepared. It has been found that nitrate and sulfate salts are most satisfactory for purposes of the present invention.

In preparing compounds of the present invention encompassed within those included in Formula I in which the di-acetyl structure is desired, that is wherein R¹ is

and A is

the selected carboxamidine salt, such as for example piperidine-1-carboxamidine sulfate, is first reacted with one equivalent of an ethanolic solution of sodium. Sodium sulfate is filtered off and the filtrate evaporated to dryness. The residue is dissolved in ether and acetic anhydride added. A precipitate of the acetate salt of the guanidine starting material is obtained by filtration. The desired product is then recoverable as the salt, such as the hydrochloride, by passing HCl gas into the filtrate and recovering the crystalline product which separates out on cooling.

Reference now to the specific examples which follow will provide a better understanding of the new compounds of the present invention and the manner in which the same are prepared:

Example I

50 gms. (0.25 mol) of 3,5-dimethylpyrazole-1-carboxamidine nitrate and 290 gms. (2.0 moles) of triethylamine are dissolved in 1 liter of dry methanol, cooled in an ice bath, 108 gms. (1.5 moles) of acetic anhydride is added in one portion and the reaction mixture allowed to stand for two hours at room temperature. The methanol is then removed in vacuo and the oil dissolved in 800 ml. of water. This solution is extracted with three 100 ml. portions of ether. The ether extracts are dried over anhydrous sodium sulfate, filtered, and evaporated in vacuo. 100 ml. of benzene is added and re-evaporated. The residue is dissolved in 600 ml. of dry ether and hydrogen chloride added until the solution indicates a pH of 2. The crystalline hydrochloride is filtered, washed with ether, and dried in vacuo over P_2O_5 . Yield of N-acetyl-3,5-dimethylpyrazole-1-carboxamidine hydrochloride is 44.8 gms. or 69%, M.P. 146-147° C. corr.

Example II

To 8.85 gms. (.05 mole) of pyrrolidine-1-carboxamidine nitrate, a solution of 1.15 gms. (.05 mole) of sodium in 100 ml. of anhydrous ethanol is added and stirred for thirty minutes while protected with a soda-lime tube. The suspension is filtered and the filtrate evaporated in vacuo. The solid residue is suspended in 200 ml. of ethyl acetate and refluxed with stirring for 20 hours. The reaction mixture is filtered and the filtrate evaporated to dryness. The residue is washed with ether and the ether insoluble portion (5.6 gms.) dissolved in 150 ml. of hot ethyl acetate. After cooling to 0° C., 3.0 gms. (38% yield) of rectangular prisms of N-acetyl-pyrrolidine-1-carboxamidine are obtained, M.P. 160-162° C. corr.

Example III

Following the method of Example II, N-acetyl-morpholine-4-carboxamidine is prepared by reacting morpholine-4-carboxamidine nitrate with an alcoholic solution of sodium followed by refluxing with ethyl acetate.

Example IV

Following the method of Example II, N-acetyl-piperidine-1-carboxamidine is prepared by reacting piperidine-1-carboxamidine nitrate with an alcoholic solution of sodium followed by refluxing with ethyl acetate.

Example V

According to the method of Example I, pyrazole-1-carboxamidine nitrate in the presence of triethylamine is reacted with acetic anhydride to produce N-acetylpyrazole-1-carboxamidine.

Example VI

Following the method of Example II, N-acetyl-1,2,3,4-tetrahydroisoquinoline-1-carboxamidine is prepared by reacting 1,2,3,4-tetrahydroisoquinoline - 1 - carboxamidine

nitrate in an alcoholic solution of sodium followed by refluxing with ethyl acetate.

Example VII

5 2.01 gms. (0.1 mole) of 3,5-dimethylpyrazole-1-carboxamidine nitrate and 19.1 gms. (0.1 mole) of p-toluenesulfonyl chloride are stirred in 60 ml. of ice water. Over a period of two days, 8.0 gms. (0.2 mole) of sodium hydroxide in 45 ml. of water is added until the pH remained at 7. The solid material is filtered, washed with water and crystallized from 200 ml. of hot 75% aqueous ethanol. N-p-tolylsulfonyl-3,5-dimethylpyrazole-1 - carboxamidine is obtained, M.P. 140-141° C. corr.

15

Following the method of the previous example, N-phenylsulfonylpyrrolidine-1-carboxamidine is prepared by reacting pyrrolidine-1-carboxamidine nitrate with benzene sulfonyl chloride.

20

Example IX

15 15.0 gms. (.04 mole) of piperidine-1-carboxamidine sulfate is stirred in 100 ml. of absolute ethanol containing 1.81 gms. (.08 mole) of sodium for 1 hour. The sodium sulfate is filtered off and the filtrate evaporated to dryness in vacuo. The residue is dissolved in 200 ml. of dry ether and 8.15 gms. (.08 mole) of acetic anhydride is added. A precipitate forms immediately and after stirring for 1 hour and filtering 6 gms. (20%) of the acetate salt of the starting material is obtained. HCl gas is passed into the filtrate and a yellow oil separates which crystallizes on scratching and cooling to 0° C. One recrystallization from 30 ml. of ethanol and 200 ml. of dry ether give 5.0 gms. or 60% yield of N,N'-diacetyl-piperidine-1-carboxamidine hydrochloride, M.P. 166-168° C. corr.

35

Example X

Following the method of Example II, N-acetyl-2,6-dimethylmorpholine-4-carboxamidine is prepared by reacting 2,6-dimethylmorpholine-4-carboxamidine sulfate with an alcoholic solution of sodium followed by refluxing with ethyl acetate.

40

Example XI

45 Following the method of Example IX, pyrrolidine-1-carboxamidine sulfate is reacted with an ethanolic solution of sodium. After filtration of sodium sulfate the filtrate is evaporated to dryness and the residue dissolved in ether to which solution acetic anhydride is added. A precipitate forms, the acetate salt of the starting material, which is removed by filtration. Passing HCl gas into the filtrate will precipitate N,N'-diacetyl-pyrrolidine-1-carboxamidine hydrochloride.

50

Example XII

55 8.85 gms. (.05 mole) of pyrrolidine-1-carboxamidine nitrate is stirred in 85 ml. of ethanol containing 1.15 gms. (.05 mole) of sodium for thirty minutes. The ethanol is evaporated in vacuo without filtration and 20 ml. of methyl octanoate added and heated on a steam bath for two hours, and allowed to stand at room temperature for three days. 200 ml. of ether is added and the insoluble material filtered and discarded. The ethereal filtrate is evaporated in vacuo and 300 ml. of pet-ether (30-60° C.) added. The solution is chilled to 0° C. overnight. 5.8 gms. (60%) of N-octanoyl-pyrrolidine-1-carboxamidine is obtained. After one recrystallization from pet-ether, 4.4 gms. (46% yield) of pure material is obtained, M.P. 70-71° C. corr.

60

Example XIII

65 According to the method previously described, N-acetyl-2,4-dimethylpiperidine-1-carboxamidine is prepared by reacting 2,4-dimethylpiperidine-1 - carboxamidine nitrate with an ethanolic solution of sodium followed by refluxing with ethyl acetate.

70

5

Example XIV

N,N'-diacetyl-2,4-dimethylpyrrolidine-1-carboxamidine is prepared according to the method of Example IX by reacting 2,4-dimethylpyrrolidine-1 - carboxamidine sulfate with an alcohol solution of sodium followed by refluxing with acetic anhydride.

Example XV

Following the method of Example VII, 2,6-diethylmorpholine-4-carboxamidine nitrate is reacted with p-toluene sulfonyl chloride to produce N-p-tolylsulfonyl-2,6-diethylmorpholine-4-carboxamidine.

Example XVI

N-acetyl-3,5-diethyl-2-pyrazoline-1-carboxamidine is prepared by reacting 3,5-diethyl-2-pyrazoline-1-carboxamidine nitrate with acetic anhydride according to the method described in Example I.

Example XVII

Following the method of Example XII, N-heptanoylpiperidine-1-carboxamidine is obtained by reacting piperidine-1-carboxamidine nitrate with an ethanol solution of sodium followed by heating the sodium containing carboxamidine with methyl heptanoate following removal of the alcohol.

Various modifications may be made in carrying out the present invention without departing from the spirit and scope thereof. Insofar as these modifications are within the purview of the attached claims, they are to be considered as part of this invention.

The invention claimed is:

1. A member of the group consisting of a compound of the formula:

wherein R represents a member of the group consisting of pyrazolo, lower alkylpyrazolo and di-lower alkylpyrazolo; R' is selected from the group consisting of hydrogen and acetyl; A is lower alkanoyl having not more than 7 carbon atoms; and the pharmaceutically acceptable acid salts thereof.

- 5 2. N-acetyl-3,5-dimethylpyrazole-1-carboxamidine.
3. N-acetylpyrazole-1-carboxamidine.
